United States Patent Office.

WILLIAM H. ECKERT AND JAMES A. BLACK, OF DAYTON, OHIO.**

Letters Patent No. 92,802, dated July 20, 1869.

IMPROVEMENT IN STATION-INDICATOR FOR RAILROAD-CARS.

The Schedule referred to in these Letters Patent and making part of the same.

To all whom it may concern:

Be it known that we, WILLIAM H. ECKERT and JAMES A. BLACK, of Dayton, in the county of Montgomery, and State of Ohio, have invented a new and improved Annunciator for Railroad-Cars; and we do hereby declare that the following is a full, clear, and exact description thereof, which will enable those skilled in the art to make and use the same, reference being had to the accompanying drawings, forming part of this specification.

The nature of this invention relates to improvements in annunciators for railroad-cars, the object of which is to improve the construction of the same.

It consists of an improved arrangement of the ratchet for operating the rollers over which the belt works, on which the names of stations are placed, and an arrangement of the said rollers whereby the belt may be kept tight, as will be more fully described on reference to the accompanying drawings, wherein—

Figure 1 represents a front view of an annunciator provided with our improvements;

Figure 2 represents a side view of the same, with the case open; and

Figure 3 represents a section on the line $x x$ of fig. 1. Similar letters of reference indicate corresponding parts.

The case A is provided with the rollers B and B', in the interior thereof, and with the case C, upon one side, in which the ratchet and pawl for operating the rollers and the alarm-bell are arranged.

D represents the ratchet, which is secured to the axis of the roller B', whereon the ratchet-lever E is also supported.

F is a spring-pawl, pivoted to the lever, for actuating the said ratchet-wheel.

G represents a spring, attached to the outer end of the lever E, for retracting the lever.

H represents the cord, for actuating the pawl, which is provided with friction-pulleys, I I, over which it works in either direction after passing out of the case.

K represents the bell, and

L, the bell-hammer, which is actuated by the ratchet D, through the lever M in one direction, and by a spring in the other.

N represents sliding bearings, arranged in grooves in each side of the case A, which support the journals of the rollers B and B', and are provided with sockets in their contiguous ends, with springs, O, which constantly tend to separate them, and thereby maintain a proper tension on the belt P, whereon the names of stations are arranged.

We claim as new, and desire to secure by Letters Patent—

The combination of the rollers B B' and belt P, when the tension of the belt is regulated by springs O, arranged between the boxes in which the journals of the rollers move, such boxes moving in grooves formed in the sides of the case, substantially as and for the purposes set forth.
